SPRAYING DEVICE

John A. Marcuse, Scarsdale, N. Y., assignor to
West Disinfecting Company, Long Island City,
N. Y.

Application November 13, 1947, Serial No. 785,605

3 Claims. (Cl. 299—58)

1

This invention relates to spraying devices, and particularly to those employed for the purpose of spraying or atomizing liquids, such as insecticides, disinfectants and other liquid preparations.

One of the objects of the invention is to provide a device of this character which will be especially adapted for the spraying of relatively large areas, such as interiors of theatres, factories, auditoriums and other large rooms or enclosures. The invention contemplates the provision of means by which a plurality of jets or sprays are simultaneously directed radially from an arcuately-arranged bank of spray nozzles, so that a cloud or mist of substantial size and of fine spray is directed from the device over a considerable area during the operation of the sprayer.

Another object of the invention is to provide a device of this character, which, while having a very substantial spraying capacity, may be made portable if desired and thus easily transported from place to place, and this, coupled with the extensive spraying capacity of the device, enables a large area to be very quickly and uniformly sprayed.

More particularly, the invention contemplates the provision of a fluid-containing receptacle of substantial capacity on which is mounted a spraying head in the form of a substantially semi-circular hollow housing having an arcuately-shaped top in which a plurality of spray nozzles are radially mounted. Compressed air is directed into the hollow housing and from the interior of the same through the nozzles, said nozzles being also connected to siphon tubes which extend from the nozzles into the fluid-containing chamber to reach the fluid therein.

These and other objects are attained by the invention, a more particular description of which will hereinafter appear and be set forth in the claims appended hereto.

In the accompanying drawings, wherein an illustrative embodiment of the invention is disclosed, Fig. 1 is a rear view, with parts in section of the spraying head with the cover member thereof shown in dotted lines; Fig. 2 is a top plan view of the structure of Fig. 1; Fig. 3 is a side view of the same; Fig. 4 is a vertical sectional view through one of the spray nozzles; Fig. 5 is a side elevation of the body portion of one of the spray nozzles; Fig. 6 is a side elevation of the cap or tip portion of the nozzle; Fig. 7 is a view looking at the under side of the body of the nozzle shown in Fig. 6; Fig. 8 is a vertical sectional view through the air distributing chamber or housing, with the cover member fitted

2

thereover, the nozzles and the upper portions of the siphon tubes being shown in phantom, and Fig. 9 is a front view of the spraying head and a portion of the top of the fluid-containing receptacle.

With reference to the drawings, 1 indicates the body of the fluid-containing receptacle, the same being preferably of substantial size and capable of being mounted, if desired, upon a small hand-pushed truck or dolly so that the spraying device may thus be moved from place to place throughout the area to be sprayed. The liquid to be sprayed is contained within the receptacle 1, which may be provided with a suitable filler opening and also with a gauge, if desired, to constantly indicate the level of the liquid contained in the receptacle.

The top member of the receptacle 1 is indicated at 3 and secured on top of the member 3, 20 by means of the screws 4 or other equivalent fastening means, is the base plate 5 of the spraying head. The spraying head includes a housing constituting an air-distributing chamber or air manifold 6, which may be a casting of one-piece construction having flanges 7 at its opposite ends by means of which it is mounted upon the plate 5 by the screws 8. The air-distributing chamber or housing 6 is of substantially semi-circular shape and is hollow and provided with a nipple 9 which is internally threaded to enable it to be coupled to the end of a pipe or conduit 10 leading from a source of air under pressure. The source of the compressed air may be a suitable stationary tank, or a small tank and air-compressor mounted on a hand truck or dolly in company with the spraying device. The compressed air is thus directed into the interior of the chamber 6 and is forced through a plurality of spray nozzles 11, the construction of which 40 will be presently set forth.

The nipple 12 in the front wall of the chamber 6 is closed by a threaded plug 13. The nozzles 11 are arranged in the manner most clearly shown in Fig. 1, namely, in substantially equally-spaced 45 relationship projecting radially from the arcuate periphery 14 of the chamber 6, said periphery being defined by the integral curved top wall 15 of the chamber 6. Thus, the radial disposition of the several nozzles 11 is such that when the spray 50 is ejected therefrom in the manner to be described, the spray will cover a very considerable area and thus the spraying of a large room or other substantial space can be very quickly and thoroughly done.

55 The construction of each of the nozzles 11 is

shown in Figs. 4 to 7 inclusive, wherein it will be noted that the nozzle is composed of three main parts, namely, a body portion 16, a gasket 17 and a cap or tip portion 18. The body portion 16 is formed with a shank 19 having threads 20 which are threadably received in a threaded aperture 20a provided in the top or arcuate wall 15 of the chamber or housing 5. Located above the threaded shank 19 of the body 16 is a hexagonal portion 21, above which is the threaded part 22 terminating at the top in the flat shoulder 23, from which arises a conical stem 24 terminating at the top in the cylindrical tip 25. Extending axially through the shank portion 20 of the body, is a central passage 26, the upper end of which is in communication with three parallel longitudinally-extending passages 27 which emerge at the shoulder 23. Extending centrally through the body of the nozzle is the longitudinally-extending air passage 28, which emerges at the tip 25, as clearly seen in Fig. 4.

At its opposite end, the air passage 28 connects to a lateral passage 29 which extends through the hexagonal portion 21 of the body and threadably receives at 30a one end of a siphon tube 30. Said siphon tube 30 extends laterally from the nozzle and is then bent downwardly, as indicated at 31 in Fig. 3 and passes through the hole 32, provided in the plate 5 and top member 3, to reach the interior of the fluid-containing receptacle 1 for access to the liquid contents 2 of the same.

The cap or tip member 18 of each of the nozzles 11 is shown in detail in Figs. 4 and 6, wherein it will be noted that the same includes the internally threaded hexagonal portion 33 which threadably engages the threads 22 on the body 16 when the cap or tip member 18 is fitted over the body. It will be observed that the cap or tip member 18 is formed with a central aperture 34 (Fig. 4) which fits around the cylindrical tip part 25 but is spaced therefrom to thereby provide an annular space 35 between the surface of the tip 25 and the inner surface of the aperture 34. Leading downwardly from the aperture 34 is a flared or tapered passage 36 which fits about but is spaced away from the surface of the tapered stem 24. When the cap member 18 is fitted in position over the end of the body 16 and is threaded down upon the threads 22 on the same, the washer or gasket 17 is compressed between the shoulder 38 on the inside of the cap and the shoulder 23 of the body 16. Said washer 17 clears the three passages 27 so that said passages communicate with the tapered passage 36 which in turn leads into the aperture 34. Thus, the air under pressure from the interior of the air-distributing chamber or housing 5 is forced through the passage 26 and through the three passages 27 and out through the communicating passages 36 and 34. Said air, passing through the annular space 35 between the tip 25 and the inner surface of the aperture 34, creates a siphoning or suction effect, so that the liquid from the fluid-containing receptacle is thus drawn upwardly through the siphon tube 30 and out through the passage 28 to be ejected in the form of a fine mist or spray at the outlet of the nozzle. The radial disposition of the several nozzles 11 is such that the sprays simultaneously ejected from the nozzles impinge against one another a distance from the outlets and a cloud of spray or mist is diffused and spread about by the sprayer to cover a wide area.

To protect the nozzles and the several siphon

tubes leading therefrom, a suitable semi-circular cover member 40 is provided which fits over the housing or chamber 5 and is fastened to the base plate 5 by means of screws or other equivalent fastening elements 41 passing through lugs 42 extending laterally from the cover member 40. In its front wall, the cover member 40 is formed with an opening 43 to clear the compressed air conduit 10. In its top or peripheral wall 44, the cover is formed with a plurality of openings 44 to expose the tip ends of the nozzles 11 and permit the free ejection of the sprays therefrom. Fig. 9 shows the front of the cover 40 wherein it will be seen that the same encloses and fully protects the parts of the spraying device.

From the foregoing, the operation of the improved spraying device will be readily understood. When the conduit 10 is connected to a suitable source of compressed air, the air, passing through the conduit 10, will enter the air-distributing chamber or housing 5 and pass out through the communicating passages 26, 27, 36 and 34 of the nozzles, creating a siphon effect which will draw the liquid up through the several siphon tubes 30 and cause it to be ejected in a fine steam or mist. The radial disposition of the nozzles will cause a substantial cloud of spray or mist to be distributed by the nozzles, thus covering a large area and effective, uniform, and thorough distribution of the material being sprayed will be had.

While I have shown and described one embodiment of the invention, it is obvious that the same is not to be restricted thereto, but is broad enough to cover all structures coming within the scope of the annexed claims.

What I claim is:

1. A spraying device of the character described comprising, a fluid-containing receptacle, an air-distributing chamber mounted on the top of and separated from said receptacle, means for directing air under pressure into said chamber, said chamber being provided with an arcuate horizontal outer wall, a plurality of spray nozzles mounted in said wall and projecting upwardly and radially from the same, said nozzles being in communication with the interior of the air chamber, a siphon tube connected at one end to each nozzle, said siphon tubes extending laterally from the nozzles and thence extending downwardly externally of the air chamber and through the top of the fluid-containing receptacle to enter the same and reach the fluid contained in said receptacle.
2. A spraying device of the character described comprising, a fluid-containing receptacle, a plate attached to the top of the same, a substantially semi-circular hollow housing attached to the top of said plate and arising from the same, an air-supply conduit entering one of the walls of the said housing to reach the interior of the housing, the housing having an arcuately-shaped horizontally disposed top wall, a plurality of spaced, upwardly and radially-extending spray nozzles mounted in said top wall of the housing, and being in communication with the interior of the housing, each of said nozzles including a siphon tube extending laterally from it on the outside of the housing and directed downwardly and passing through the plate and entering the interior of the fluid-containing receptacle and reaching the fluid contained in the same.
3. A spraying device of the character described comprising, a fluid-containing receptacle, an air-distributing chamber mounted on top of and

separated from said receptacle, said chamber being substantially semi-circular and having a flat bottom secured to and resting on top of the fluid container, said air-distributing chamber being provided with an arcuately-shaped top, said chamber having vertically-disposed side walls, an air-supply conduit entering one of the side walls of the air-distributing chamber to reach the interior of the same and convey air under pressure thereto, a plurality of spaced, upwardly and radially-extending spray nozzles mounted in the arcuate top of the air-distributing chamber and being in communication with the interior of said chamber, each of said nozzles including a siphon tube extending laterally from it on the outside of the air-distributing chamber and directed downwardly and entering into the interior of the fluid-containing receptacle and reaching the fluid contained within the same, and a substantially semi-circular cover member fitted over the air-distributing chamber and nozzles and parts of the

siphon tubes, said cover member being apertured to expose the outlet ends of the spray nozzles.
